UNITED STATES PATENT OFFICE.

ETIENNE CHALLET, OF GENEVA, SWITZERLAND, ASSIGNOR TO L. HELLER & SON, OF NEW YORK, N. Y.

MACHINE FOR FIXING PRECIOUS STONES ON THE STONE-CARRIERS EMPLOYED IN LAPIDARY OPERATIONS.

1,261,766.

Specification of Letters Patent.

Patented Apr. 9, 1918.

Application filed November 10, 1915. Serial No. 60,694.

To all whom it may concern:

Be it known that I, ETIENNE CHALLET, citizen of Switzerland, residing at Geneva, Switzerland, have invented certain new and useful Improvements in Machines for Fixing Precious Stones on the Stone-Carriers Employed in Lapidary Operations; and I do hereby declare the following to be a full, clear, and exact description of the invention, such as will enable others skilled in the art to which it appertains to make and use the same, reference being had to the accompanying drawings, and to figures of reference marked thereon, which form a part of this specification.

The present invention relates to a machine which serves for fixing precious stones on the stone carriers in the different lapidary operations to which the rough stones are subjected successively to impart a regular form with polished facets thereto.

This machine enables the stone to be perfectly centered on the extremity of the stone carrier and to fix it solidly thereto, which is of great importance if the cutting and polishing of the stone is effected by means of automatic machines.

In the accompanying drawing a suitable form of machine for carrying out the object of this invention is illustrated.

Similar letters refer to similar parts throughout the different views.

Figure 1 is an elevation with certain parts shown in section.

Fig. 2 shows in longitudinal section and to a larger scale, a stone carrying dop or spindle and different parts of the machine in the position in which the fixing of the stone on the extremity of said stone carrier is effected.

Fig. 3 is an elevation of a stone carrier fitted with a stone and

Fig. 4 a plan of the extremity of the stone carrier which receives the stone.

The machine comprises a frame formed of a foot 1, two vertical columns 2 and a movable receptacle 3 guided by the said columns. In the foot is provided a mold serving to receive the stone 4 and at the base of the receptacle 3 a channel 5 serves to direct hot wax, through the stone carrier, into the said mold. For this purpose, the stone carrier 6 is of tubular form and the movable receptacle 3 is connected by a part 7 to a

lever 8 pivoted at 9 to the foot of the machine. A gripper composed of a fixed part 10 forming part of the foot 1 and of a movable part 11, having two fingers, serves to maintain the stone carrier in the vertical position above the mold which allows of the introduction of the channel 5 conveying the wax to the end of the stone carrier. The part 11 of the gripper is spring actuated; it is pivoted to a stem 12 and its handle 13 enables the gripper to be opened for the placing in position and removal of the stone carriers.

The channel 5 communicates with the wax receptacle 3 through a chamber 14 in which the wax is heated by means of a worm for hot oil 15 surrounding the lower part of this chamber, the upper part of which is cooled by a cold water circulation 16 to avoid the heat being transmitted to the wax in powder contained in the receptacle 3 and prevent its automatic descent. A piston 17, mounted in the receptacle 3 and connected to a spring lever 18 enables the wax to be supplied to the chamber 14 and serves to force it down through the channel 5 into the mold and to there form under pressure the block of wax which is to retain the stone previously introduced into the bottom of the mold, on the extremity of the stone carrier.

The receptacle 3, the chamber 14 serving to heat the wax, the piston 17 with its operating lever and the channel 5 together form an injector which may be lowered on the columns 2 for the introduction of the channel into the stone carrier. The extremity of this latter may thus be brought against the annular stop 19, which is situated in the interior of the stone carrier and which prevents the wax under pressure from remounting in the tube of the stone carrier.

The mold is formed by a ring 20, fixed in the foot 1 of the frame, and by a movable and interchangeable bottom constituted by a short rod 21. This bottom comprises a conical part 22 continued by a cylindrical part 23 and a dish 24 inclined toward the center. The cylindrical part is of very small height; it serves to center the stone in the mold by its waist. With regard to the dish 24, the inclination of which varies with the bevel of the stone, it serves to impart to the latter the seating necessary to prevent the stone becoming deflected on its

waist (filleti) by the pressure of the wax compressed by means of the lever 18. The rod 21 rests on the short arm of a lever 25, pivoted at 26, which allows it to be raised 5 by hand, or by means of a pedal, and of thus detaching the block of wax from the ring 20 forming part of the mold. The mouth 27 of the mold is beveled and closed by the head 28 of the stone carrier when introduced. 10 On the face of this head are cut radial grooves 29 which serve to retain the solidified block of wax 30 and which further enable the workman to see when the operation is terminated for, when the mold is full, 15 the wax escapes through these grooves and rises in fine threads through the beveled mouth 27 of the mold under the pressure exerted by the piston 17.

The receptacle 3 is normally held at the 20 top of the columns 2 by the flow and return conduits of the hot oil worm 15 which are of hardened copper and of a certain length to be able to act as a spring.

The machine operates as follows:

25 The receptacle 3 being filled with powdered wax and a heated stone carrier placed in position within the gripper 11 the lever 8 is depressed with one hand to bring the passage 5 to the bottom of the stone carrier, 30 and then, with the other hand the lever 18 is depressed in order, through the piston 17, to drive the wax through the passage into the mold, in the bottom of which the heated stone 4 has been previously introduced. A 35 strong pressure is continued to be exerted upon the lever 18 until wax is seen to issue through the groove 29 in the head of the stone carrier. At this moment the molding is completed; the two levers 8 and 18 are 40 released and allow the receptacle 3 to resume its position of rest at the top of the columns 2. Then the removal from the mold is effected by the aid of lever 25 which is depressed so as to raise the bottom 21, which 45 causes the block of wax to be forced out of the mold with the stone firmly embedded therein.

Having thus described my said invention, what I claim and desire to secure by Letters 50 Patent of the United States is:

1. A machine for fixing precious stones in the stone carriers, employed in lapidary operations, embodying therein a mold adapted to receive a stone, a receptacle for wax or 55 other suitable cement, a cylinder communicating with said receptacle, a nozzle leading from said cylinder and adapted to enter the stone carrier, means positioning a stone carrier relatively to said mold and said nozzle 60 and means whereby said wax or other cement may be forced from said cylinder, through said carrier into the mold and about the end of said carrier and a stone in the mold.

2. A machine for fixing precious stones in 65 the stone carriers employed in lapidary op-

erations, embodying therein a mold adapted to receive a stone, a receptacle for wax or other suitable cement, a cylinder communicating with said receptacle, a nozzle leading from said cylinder and adapted to enter the 70 stone carrier, means adjacent said cylinder for heating wax or other cement delivered thereto, means positioning a stone carrier relatively to said mold and said nozzle and means whereby said wax or other cement 75 may be forced from said cylinder through said carrier into the mold and about the end of said carrier and a stone in the mold.

3. A machine for fixing precious stones in the stone carriers employed in lapidary operations, embodying therein a mold adapted to receive a stone, a receptacle for wax or other suitable cement, a cylinder communicating with said receptacle, a nozzle leading from said cylinder and adapted to enter 80 the stone carrier, means adjacent said cylinder for heating wax or other cement delivered thereto, means positioning a stone carrier relatively to said mold and said nozzle, 85 means whereby said receptacle, said cylinder and said nozzle may be moved toward and from said mold, and means whereby said wax or other cement may be forced from said cylinder, through said carrier into the mold and about the end of said carrier and 90 a stone in the mold.

4. A machine for fixing precious stones in the stone carriers, employed in lapidary operations embodying therein a mold adapted to receive a stone, a receptacle for wax or 100 other suitable cement, a cylinder communicating with said receptacle, a nozzle leading from said cylinder and adapted to enter the stone carrier, means adjacent said cylinder for heating wax or other cement delivered thereto, means cooling said receptacle adjacent said cylinder whereby granular wax or other cement may be stored in said receptacle and delivered in granular form to said cylinder, means positioning a stone carrier relatively to said mold and said nozzle and means whereby said wax or other cement may be forced from said cylinder through said carrier into the mold and about 105 the end of said carrier and a stone in the 110 mold.

5. A machine fixing precious stones in the stone carriers used in lapidary operations, embodying therein a mold having a conical bottom adapted to receive a stone, vertical 120 guides, a reciprocatory receptacle mounted thereon, a cylinder communicating with said receptacle and movable therewith, a discharge nozzle leading from said cylinder and adapted to enter the stone carrier, means 125 positioning a stone carrier relatively to said nozzle and said mold, said nozzle being axially alined with said conical bottom, a piston mounted in said cylinder and independently operative hand levers whereby said re- 130

- ceptacle may be moved toward and from said mold, and said piston may be actuated to permit wax or other cement to flow from said receptacle into said cylinder, or to eject 5 wax therefrom through said nozzle into the mold and about the stone and the lower face of the stone carrier.
6. A machine for fixing precious stones in the stone carriers used in lapidary operations, embodying therein a tubular, metallic stone carrier having an enlarged head, the lower face of which head has a plurality of 10 radially extending channels formed therein whereby the wax securing the stone in said carrier is retained in relation to said carrier.
- In testimony, that I claim the foregoing I have hereunto set my hand this sixteenth day of September, 1915.

ETIENNE CHALLET.
